FLOATING BOLT LATCH

Waldemar A. Endter, Long Beach, Calif.

Application May 27, 1946, Serial No. 672,582

5 Claims. (Cl. 292—223)

1

This invention has to do with improvements in latch mechanism of the take-up type characterized by the use of a "floating bolt" having capacity for both swinging and bodily movement in a latching action resulting in the closure (assuming it to carry the bolt) being urged in a closing direction with relation to its keeper.

Particularly the invention aims to simplify, improve and economise manufacture of the type of latch mechanisms disclosed in my Patent No. 2,376,992 issued May 29, 1945, to me on "Latch Device," and in my copending applications Serial Number 597,097, filed June 1, 1945, and Serial Number 640,859, filed January 12, 1946.

One major object of the present invention is to simplify the form and mounting of the bolt, in respects representing substantial economies in mass production of the latch, while maintaining its operating efficiency and distinctive functional characteristics. Like the forms of latches disclosed in the patent and applications referred to above, the present mechanism utilizes a bolt or associated part, which, by virtue of its capacity for floating or bodily movement, is brought to bear against a relatively stationary (e. g. door-carried) abutment to transmit a closing thrust against the abutment while the reactive force is taken by the keeper. In further simplification of the previous forms, the present invention contemplates loosely retaining the bolt within the latch housing, in a manner obviating the necessity for bolt mountings involving the use of closely fitting parts or exact machining operations.

Additional objects are directed to the keeper and bolt combination, and particularly curved keeper surface shapes which serve such functions as to assure retention of the bolt against inadvertent release from either or both initial and advanced latched positions, and to present camming surfaces acting to thrust the bolt against the abutment while maintaining the bolt in blocking relation to opening movement of the closure.

All the objects and details of the invention will be understood from the following description of certain preferred forms, shown typically in mechanisms designed for use as automobile door latches, illustrated by the accompanying drawings, in which:

Fig. 1 is a section taken on line 1—1 of Fig. 2 through the bolt assembly, and illustrating in elevation the associate control mechanism;

2

Fig. 2 is a section on line 2—2 of Fig. 1;

Figs. 3 and 4 are end and side views, respectively, of the bolt;

Figs. 5 and 6 are end and side views, respectively, of the bolt control part;

Figs. 7 and 8 are enlarged cross-sections on line 7—7 of Fig. 1 showing different bolt and keeper positions;

Figs. 9 and 10 are similar views illustrating a variational form of the invention; and

Fig. 11 is a view like Fig. 9 showing an additional variational form.

For adaptation to an automobile door, the latch mechanism as shown in Figs. 1 and 2, is mounted in a case structure 10 of the usual form comprising right angle flanges 11 and 12, the former of which carries the bolt and shaft assembly 13 at the door edge, flange 12 carrying the bolt control and locking mechanisms generally indicated at 14. Opening 15 in flange 11 contains the outwardly projecting bolt-containing bracket or semi-housing 16, which may be of the usual form adapted for reception in confinement between the keeper parts, as later described.

25 The bolt 17, detailed in Figs. 3 and 4, is mounted within the housing 16 for pivotal or swinging and bodily movement, one significant characteristic of the bolt mounting being that it permits free displacement of the bolt under the influence of the later described keeper, spring and stationary abutment. A pin 18 terminally secured within the housing 16 and the stationary deck plate 19, extends through an opening 20 in the bolt, which may have the form of a slot extending generally in the direction of bodily displacement of the bolt, and for example at an angle of 30 degrees from the vertical in the home position of the bolt. Thus, except as the bolt may be restrained by spring 21 and the housing 16, it is freely displaceable, the pin 18 serving merely as a retainer and guide. As shown in Fig. 1, the bolt extends through the case flange 11 and housing 16, and has a shoulder 22 engageable against the bottom horizontal edge 23 of opening 15 to limit rotation of the bolt in a latching direction.

30 35 40 45 50 The bolt has an associated control part, which for convenience of manufacture and assembly preferably is made as a separate element 24, see Figs. 5 and 6, carried by the inner end of the bolt. The control part has an opening 25 which receives the correspondingly shaped end projection

26 on the bolt so that the parts are interengaged against relative rotation. The element 24 carries an arm 27 engaged by coil spring 21 mounted at 28 on the case flange 11, the spring exerting a constant thrust resisting anti-latching rotation of the bolt, and tending, in the latched positions of the bolt, to progressively advance the latter into or along the keeper. Element 24 carries a second, laterally projecting arm or lug 29 engaged by parts of the mechanism 14 to control the bolt operation in the manner later explained.

Referring to Fig. 7 the pillar-carried keeper assembly 30 comprises a plate 31 carrying the spaced horizontally disposed lug 32 and bolt retaining keeper 33 between which the housing and bolt assembly is received to effect a dove-tail latched relation of the parts, the bolt 17 being received within the keeper and exerting against the latter a thrust forcing the housing 18 into tight engagement with the under surface of the lug 32. The keeper 33 has a concavely curved bolt engaging face 34 which has a camming relation to the curved bolt surface 35, such that latching advancement of the bolt along surface 34 tends to bodily displace the bolt generally in the direction of elongation of the slot 20. The bolt has what may be termed a safety catch surface 35a offset radially inward from the surface 35 and curved in conformity with the upper curved portion 34a of the keeper surface, so that the surfaces interfit at the position shown in Fig. 8 in such relation to the housing thrust against the bolt and the transmission of the bolt thrust against the keeper, as to provide against any tendency for the bolt to release.

Assuming the door to be open with the bolt position established by the engagement of its surface 22 against edge 23 of the case opening, as the closure is swung shut, the bolt face 36 engages the end 37 of the keeper, displacing the bolt upwardly until it overrides the top rounded edge 38 of the keeper, whereupon spring 21 acts to advance the bolt into the keeper to the safety catch position of Fig. 8. As the closure is shut further the bolt overrides the keeper to the position at which its surface 35 is advanced into and along the keeper surface 34, the spring 21 exerting a progressive take-up action tending to crowd the door against the usual cushion as the bolt approaches the home position shown in Fig. 7. By reason of the camming relation of the keeper and bolt surfaces 34 and 35, the bolt is bodily displaced to bring its curved surface 40 into engagement with a stationary abutment presented by the inside surface of the housing 18. Accordingly, in all of its latched positions (including the safety catch position), the bolt serves to block opening movement of the door by reason of the interposition of the bolt between the pillar-carried keeper 33 and the door-carried abutment 18.

From the foregoing it will be understood that during latching rotation of the bolt after it enters the keeper, the bolt has rocking and sliding engagement with the stationary housing surface 18a. At the same time the bolt rocks and slides about the pin 18 by reason of the shifting fulcrum or line of contact between the underside of the pin and the lower sidewall of the slot or opening 20 in the bolt. The curved bolt surface 40 progressively makes line contact with the inside surface of the housing, but this contact is utilized to effectively resist anti-latching rotation of the bolt in any of its latched positions.

This result is achieved by shaping or slanting the engaged housing surface to make the angle between a tangent to the curved bolt surface 40, at its line of contact with the housing, and the line of bolt reaction thrust (effected by the thrust of the bolt against the keeper) extending through the fulcrum point of the bolt less than 90°. The interengagement of the bolt and housing surfaces may be utilized to positively assure against inadvertent release of the bolt from latched condition within the keeper, as by the provision more particularly constituting the subject matter of my copending application Ser. No. 640,859, referred to above. For this purpose, the bolt surface 40 may have a flattened or straight-line portion 40a engageable against the flat or straight-line surface 18b of the housing at an early or initial latched position of the bolt, as shown by the dotted lines. Because of the flat surface interengagement of the bolt and abutment faces 40a and 18b, anti-latching rotation of the bolt out of the keeper is effectively resisted against any combination of pressure and vibration applied to the door or otherwise tending to release the bolt.

In accordance with the variational form of the invention shown in Figs. 9 and 10, the bolt 41 has a circular, relatively large diameter opening 41 loosely receiving the pin 42 to permit free relative bodily displacement of the bolt. Here the bolt has a true segmental circular curved keeper engaging face 43 having its center of curvature at the center of opening 41. The keeper 44 has a concave bolt engaged face 45, the upper portion 45a of which has a circular curvature corresponding to the curvature of the bolt surface 43, so that in the initial latched position of Fig. 10, the bolt and keeper interengage along a common arc centered at the center of rotation of the bolt. A thrust and reactance relation thus is established between the bolt and keeper, preventing anti-latching rotation of the bolt out of the keeper as a result of pressure applied to the door. In referring to the keeper surface 45a as having a curvature corresponding to the bolt curvature (and the following applies as well to the relation between the bolt and cam surfaces 35a and 34a in Figs. 7 and 8), it is appreciated that the same security against unintentional release of the bolt may be had by giving the keeper surface 45a greater concave curvature, always, however, in a direction or to a degree such that the keeper reactance against the bolt tends either to cause no rotation of the bolt, or to rotate the bolt in a latching, as distinguished from an anti-latching direction. More specifically the angle between a tangent to the keeper surface, at its line of contact with the bolt, and a line extending from said line of contact through the fulcrum point of the bolt should be 90° or less, such angle being measured on that side of the line through the fulcrum point facing in the direction of anti-latching rotation of the bolt. In other words, the keeper surface 45a should be slanted or inclined with respect to the bolt surface 43 to provide a latching force component to the bolt by keeper reactance against the bolt. Beyond the curved face 45a, the keeper has a cam surface 45b which tends, during bolt advancement toward the home position, to bodily displace the bolt with the curved bolt surface 40 bearing against the inside face of the housing 18. Upon reaching the fully latched position of Fig. 9, the bolt moves beyond and below the reversely

curved end surface 45c of the keeper, with the result that the bolt becomes blocked against inadvertent anti-latching rotation, the curvature of surface 45c and its position in the path of the bolt, tending, under the influence of pressure exerted against the door, to cause the bolt to turn further in a latching direction.

The keeper and bolt parts shown in Fig. 11 are similar to the form of Figs. 9 and 10, except with respect to the shape of the keeper surface engaged by the bolt in its home position. Here the circularly curved bolt surface 80 is engageable against the correspondingly curved keeper surface 81 in an initial latched position corresponding to Fig. 10. Then as the bolt, with its curved surface 82 engaging the abutment surface of the housing 16, is advanced in a latching direction, the bolt surface has camming engagement against the substantially straight keeper surface 83 of reduced angularity substantially as shown. This surface angularity is such as to effect a forceful take-up action, and also to assure against unintentional release of the bolt from advanced latched or home position. It will be observed that the housing thrust against the bolt surface 82 at point 84 is at a location above the point of engagement at 85 between the bolt and the pin 86, and that the housing thrust is normal to a tangent to the curved surface 82 at the point 84. Accordingly, any opening tendency of the door, without intentional release of the bolt, is resisted by the transmission of a thrust from the housing 16 tending to rotate the bolt in a latching direction. Influenced also by the relatively high coefficient of friction between the housing and bolt at point 84, the bolt will remain engaged with the keeper surface 83, until intentionally released.

The invention contemplates the provision of any suitable means for serving the purposes of the mechanism 14, to manually effect the bolt release from the keeper and to maintain separate combinations of the parts of the entire assembly in locked or ineffective conditions. Merely as illustrative, the mechanism 14 is shown to have the construction and operation more fully developed in my copending application Serial Number 640,860, entitled Lock Control Mechanism, filed January 12, 1946. For present purposes, a general description of the operating and control mechanism 14 will suffice.

The control mechanism includes the usual outside handle or operator (not shown) carried on a spindle 48 supported by the bracket 49 and carrying an arm 50 to which is pivotally attached at 51 the bifurcated bodily movable element 52. The usual inside door handle or operator (not shown) reciprocally actuates the link 521. Also for operation at the inside door is provided the usual push button rod 53. Bolt 17 is operated by a bell crank actuating lever 54 pivoted on the stationary pin 55 and having a bifurcated arm 56 carrying lugs 57 and 58 engaging and receiving between them lug 29 on the bolt control part 24. Thus the bolt and actuating lever 54 are associated or interconnected for rotation, one in response to movement of the other. Lever 54 carries a lug 59 engaged by the end of coil spring 60 carried on the pin 55, the spring tending to urge the lever in an anti-latching direction and to take up looseness in the lever engagement with associated parts.

Pin 55 also carries the pivoted control lever 61 having an arm 62 pivotally attached to the push

button rod 53, and having a second arm 63 engageable by the key-controlled rotor 64 carried on spindle 65, to throw the lever between its locking and releasing positions. An over-center coil spring 66 connects arm 63 to the case flange 12.

Rotation of spindle 48 by the outside operator swings arm 50 and element 52 down against the resistance of spring 67, producing anti-latching rotation of the bolt by the engagement of shoulder 68 on the arm 63 against the actuating lever lug 57, the starting positions of the parts being as in Fig. 1. The bolt is similarly releasable by operation of the inside door handle, causing movement to the left of link 521 and resultant swinging of lever 54 to rotate its lug 57 against the bolt part arm 29.

To lock the latch mechanism at the inside, depression of the push button rod 53 rotates lever 61 counter-clockwise, causing its lug 70 to engage against arm 71 of the element 52, swinging the latter about pin 51, a distance sufficient to clear shoulder 68 from the lug 57. The outside operator then remains freely rotatable but ineffective to release the bolt. The same rotation of lever 61 locks link 521 against retractive movement by lug 72 being brought down at the outside of and adjacent to the hook-shaped arm 73. As will be apparent, the lever 61 may be key-actuated from the outside of the door and in a manner similar to its operation by the push button lever, by rotation of the key-controlled spindle 65 and rotor 64 to engage and swing arm 63 within the limits presented by the stops 74 and 75. Finally, it may be observed that assuming the door to be opened and with the bolt and control parts in the positions of Fig. 1, the capacity of element 52 for pivotal movement and the lost motion pin and slot connection at 76 between link 521 and arm 54, permit anti-latching rotation of the actuating lever and return of the parts to normal operating positions as the bolt enters the keeper.

I claim:

1. In a latch mechanism for a stationary member and a swinging closure member, the combination comprising: a pivot pin adapted to be mounted on one of the members; a bolt having a bearing opening of larger size than and receiving said pin to mount said bolt for rotation and radial bodily displacement thereon, said bolt having a convexly curved peripheral surface portion for rotative latching engagement with a keeper mounted on the other of the members and another convexly curved surface portion peripherally spaced from and approximately opposite said keeper-engaging surface portion; and means adapted to be fixedly mounted on the one member and defining an abutment surface progressively engageable by said other bolt surface portion, by the bodily displacement of said bolt upon engagement thereof with the keeper, to resist anti-latching rotation of said bolt, the angle between a tangent to said other bolt surface at its line of abutment surface engagement and the line of keeper-engaging reaction thrust of said bolt extending through the line of rotative bolt engagement with said pin being less than 90°.

2. The structure defined in claim 1 in which the keeper-engaging bolt surface portion is cam shaped to progressively bodily displace the bolt against the abutment surface upon rotation of said bolt into latching engagement with the keeper.

3. The structure defined in claim 1 in which the abutment surface and the other bolt surface portion have flats engageable in an initially latched position of the bolt.

4. The structure defined in claim 1 in which the keeper-engaging bolt surface portion is arcuate having its center of curvature at the center of the bearing opening, and including a keeper having a concavely curved bolt-engaging surface, the initially bolt-engaged portion of which is complementary to said bolt surface.

5. The structure defined in claim 1 in which the keeper-engaging bolt surface portion is arcuate having its center of curvature at the center of the bearing opening, and including a keeper having a concavely curved bolt-engaging surface, the initially bolt-engaged portion of which is complementary to said bolt surface and the remaining portion of which has a progressively increasing radius of curvature.
